[57] CLAIM

The ornamental design for a combined bottle and closure, as
shown and described.

DESCRIPTION

FIG. 1 is a front elevational view of a combined bottle and
closure showing our new design;FIG. 2 is a right side elevational view of the combined bottle
and closure, the left side is mirror image thereto;

FIG. 3 is a top plan view thereof;

FIG. 4 is a bottom plan view thereof; and,

FIG. 5 is a top front perspective view shown with the closure
in the opened position.The portion of the rear of the combined bottle and closure
that is not shown in the drawings does not form part of the
claimed design.
